CLOSURE CAP

Jack W. Soffer, St. Louis, Mo., and Donald M. Kitterman,
Kansas City, Kans., assignors to Development Research,
Inc., St. Louis, Mo., a corporation of Missouri

Application October 10, 1956, Serial No. 43,308

Term of patent 14 years

(Cl. D58—26)

FIG. 1.

FIG. 2.

FIG. 3.

We claim:

The ornamental design for a closure cap, substantially as shown.
